UNITED STATES PATENT OFFICE.

MILTON D. BROWN, OF SAN FRANCISCO, CALIFORNIA, ASSIGNOR OF ONE-HALF TO
CHARLES V. BARFIELD, OF SAN FRANCISCO, CALIFORNIA.

SIFTER.

1,416,260.

Specification of Letters Patent. Patented May 16, 1922.

Application filed August 17, 1920. Serial No. 404,266.

To all whom it may concern:

Be it known that MILTON D. BROWN, a citizen of the United States, residing at San Francisco, in the county of San Francisco and State of California, has invented certain new and useful Improvements in Sifters, of which the following is a specification, reference being had to the accompanying drawings.

10 This invention relates to sifters and more particularly to means for closing one end of the sifter to prevent the escape of matter.

An object of the invention is to provide a device of this character particularly adapted 15 for use in connection with flour sifters wherein the perforated bottom of the sifter is covered to prevent the escape of flour, by means of a pair of movable plates which are manually operable to open the bottom of the sifter 20 and automatically operable to close the bottom of the sifter.

Another object of the invention is to provide means of this character which may be adjusted to increase or decrease the size of 25 the opening through which the flour passes and in this way permit the device to be used for depositing flour in vessels of various sizes.

Another object is to provide means of this 30 character wherein the plates for closing the bottom of the sifter are provided with a pair of links which are rigidly secured thereto, said links inclining upwardly and being arranged to limit the closing movement of 35 said plates without providing stops or like mechanisms.

A still further object of the invention is to provide means of this character including an operating rod which is freely mounted 40 within the sifter and positioned closely adjacent the handle so that the same may be operated by the finger of the user to keep simultaneous movement of the plates away from each other.

45 With these and other objects in view, the invention consists in the improved construction and arrangement of parts to be herein-after more particularly described, fully claimed and illustrated in the accompanying 50 drawings, in which:—

Figure 1 is a vertical sectional view through a sifter, showing the position of the operating means.

Figure 2 is a vertical elevation of a sifter, a portion of the sifter being cut away to 55 show the interior mechanism, and,

Figure 3 is a bottom plan view of the closure plates.

Referring to the drawings, 5 designates a receptacle such as used in sifting flour and like articles of food, the receptacle being open at its ends, and having the usual screen bottom A, a beating mechanism B being journaled within the receptacle. The parts just described, form no portion of my invention.

The lower end 6 of the receptacle is provided with a pair of inwardly directed flanges or plates 7, the outer edges of the plates corresponding to the contour of the 70 receptacle while the inner edges 8 are disposed in spaced parallel relation to each other.

In order to close the end 6 of the sifter to prevent the escape of flour when the sifter 75 is not in use I provide a pair of closure plates 9, the ends of said plates corresponding to the contour of the receptacle while the outer edges 10 and inner edges 11 are disposed in parallel relation to the edges 8, 80 the edges 10 being hinged as at 12 to the edges 8. The inner edge 11 of one of said plates is intended to overlap the inner edge of the adjacent plate when said plates are in their closed position. The movement of 85 the plates 9 is controlled by means of links 13. Each link is pivoted at its end 13^a to ears 14 carried by the inner surface of the plate adjacent the hinged edge of said plate. The end 14^a of each link is formed into a 90 loop.

Disposed within the receptacle 5 adjacent the handle and top thereof is a bracket 15 on which a cylinder 16 is disposed. Slidably mounted in the cylinder and extending 95 longitudinally of the receptacle is an operating shaft 17 having its end 18 formed into a loop adapted to receive and support the loops 14^a of the links 13. The portion of the shaft 17 disposed within the cylinder 100 16 is surrounded by a spring 19, one of said springs resting on the bracket 15 while the other end engages a finger piece 20 secured to the end of the shaft 17. By disposing the shaft 17 inwardly of the receptacle, the 105 same is protected from damage as it is pro-

tected from contact with other objects so that careless use of the device will not interfere with the operation of the shaft 17. In use of the device, the sifting mechanism is operated in the usual manner to sift the flour through the perforated bottom A. If desired, the plates 9 can remain in their closed position during the sifting operation, or the finger piece 20 may be depressed by the finger of the user so as to cause the shaft 17 to force the links 13 downwardly to separate the plates 9. In view of the inclined position of the body portion of each link, the plates can be adjusted to provide an opening sufficient to permit the flour to pass into a small receptacle or a large receptacle without causing waste, and as the plates are hinged at their outer ends, they form a funnel to properly direct the flour. The discharge of flour can be instantly stopped even during the sifting operation by simply releasing the finger piece 20 whereupon the spring 19 will force the plates 9 upwardly to close the bottom 25 of the sifter, it being impossible for flour to sift through the inner ends of the plates as they over-lap each other. It will be noted that no stop of any kind is carried by the shaft 17 or finger piece 20, this extra part being unnecessary as the particular inclined position of the links 13 together with the over-lapping edges of the plates prevents the same from moving inwardly of the receptacle to an extent greater than that necessary to close the bottom thereof. In addition to this it will be noted that the loop 18 of the shaft 17 is relatively large so as to provide all the play necessary for the loops 14 in their pivotal movement. Another feature is that the links 13 when the bottom is closed are disposed in convergent relation, and are gradually extended into alignment according to the downward

movement of the shaft 17. This novel construction also prevents the links from reaching a dead center so that locking of the plates in an open position is impossible. 45

From the foregoing it will be readily seen that this invention provides a novel means for closing the bottom of a sifter 50 to prevent unnecessary discharge and waste of flour when the sifter is in use and at the same time preventing the entrance of dirt and foreign matter as well as providing a funnel to direct the discharge of the flour. 55 All of the parts of the device are compactly arranged and so disposed within the receptacle that they do not obstruct the passage of flour therefrom.

What is claimed is:— 60

A flour sifter of the character described comprising a receptacle, sifting means disposed within said receptacle adjacent the bottom of the receptacle, a pair of plates hinged to said bottom, a link pivoted at 65 one end to each of the plates adjacent the hinged connection of the plates, each of said links being extended upwardly within the receptacle and toward the inner edges of the plates, a socket disposed inwardly of the receptacle adjacent the top thereof, a rod slidably in said socket and beyond the bottom of the socket, the opposite end of the rod being formed into a relatively large loop, the opposite end of each of said links 70 having an eye adapted to receive a portion of said loop, said eyes being arranged for movement toward and away from each other, and longitudinally of the loop whereby the links may move upon the loop from 75 the lower intermediate portion thereof to the junction of the loop with the rod.

In testimony whereof I hereunto affix my signature.

MILTON D. BROWN.
